UNITED STATES PATENT OFFICE.

JOSEPH E. DUNN, OF PHILADELPHIA, PENNSYLVANIA.

EVAPORATING AND CONCENTRATING APPARATUS.

995,776.

Specification of Letters Patent. Patented June 20, 1911.

Application filed July 18, 1910. Serial No. 572,536.

To all whom it may concern:

Be it known that I, JOSEPH E. DUNN, a British subject, residing at Philadelphia, in the county of Philadelphia and State of Pennsylvania, have invented certain Improvements in Evaporating and Concentrating Apparatus, of which the following is a specification.

My improvements are designed for use primarily with evaporating and concentrating apparatus of the ascending film type, but features thereof may be used with bulk circulating apparatus which returns liquid for recirculation, my object being to increase the efficiency of apparatus of both types.

Leading purposes of my improvements are to withdraw vapor initially from the heated fluid to be treated and to siphon the films by further vapor created in the separated liquid by its contact with evaporating surfaces.

In the preferred embodiment of my invention, the fluid to be treated is delivered to an expansion chamber, whence the liquid descends to a supply chamber and the vapor ascends to a separating chamber connected with the supply chamber by externally heated evaporating tubes containing internally heated evaporating tubes, vapor being produced in the liquid in the supply chamber by contact with heating surfaces and films or thin layers of liquid being carried upwardly from the supply chamber over the heating surfaces to the separating chamber.

My invention comprises the foregoing characteristics and special features adapted to be used therewith, which are fully disclosed in the following description and the accompanying drawings in illustration thereof.

In the drawings, Figure 1 is a sectional elevation of a multiple effect apparatus embodying my improvements; Fig. 2 is a sectional elevation of an effect having a modified construction; Fig. 3 is a sectional elevation of an effect representing a further form of my improvements; and Fig. 4 is a sectional elevation of the tops of concentric tubes with means for supporting them.

The apparatus, as represented in Fig. 1, comprises a duct 1 which delivers fluid to be treated to a separator comprising the expansion chamber 2 having its bottom connected by a duct 3 with a supply chamber 4 and its top connected by a duct 5 with a

separating chamber 6, the supply chamber being connected with the separating chamber by evaporating tubes 7 passing through the sheets 8 and 9 forming the ends of the heating chamber 10 which incloses the tubes. The chamber 10, to which steam is supplied by a conduit 11, is connected by a duct 12 with a heating chamber 13 separated from the supply chamber 4 by the sheet 14. 65 Tubes 15, communicating with the chamber 13, are set in the sheet 14 and extend upwardly within the tubes 7, preferably to terminations below the tops of the latter, the tops of the inner tubes being held in position by spiders 16 (Fig. 4). These tubes 15 have their tops closed excepting small vents 17 adapted for passing any substantial amount of air without passing vapor therethrough. 75

The tubes 7 extend well into the supply chamber 4 and have their lower ends disposed beneath the discharge end of the duct 3. A baffle 18 is placed in the supply chamber, around the lower end of the tubes, so as 80 to distribute the discharge from the duct 3, the duct discharging against the baffle. A baffle 19, within the chamber 6, surrounds the upper ends of the tubes 7, which extend through the sheet 9 into the separating chamber, the baffle having a lip 19' extending outwardly and downwardly from the top thereof. A baffle 20, having the centrally disposed inverted cone 20' and the skirt 20'' extending outwardly and downwardly, is supported in the separating chamber above the tubes 7 by a shaft 21 vertically adjustable in bearings 22 and 23 by the wheel 24. 90

A baffle 25 is supported within the chamber 6 above the smaller baffle 20, the larger baffle being of such diameter that a comparatively narrow space 26 is left between it and the wall of the separating chamber for the escape of vapor to the top of the chamber. 100 Tubes 28 provide passages for liquid on the flat baffle 25 to the bottom of the separating chamber. A vapor conduit 27 leads from the top of the separating chamber, above the baffle 25, and a liquid duct 29 leads from the bottom of the separating chamber, below the top of the baffle 19. The pipe 29 discharges to a second effect comprising an expansion chamber 2^a connected by a duct 3^a with a supply chamber 4^a and by a duct 5^a with the separating chamber 6^a; the supply chamber being connected with the separating chamber 110

ber by tubes 7^a which pass through the heating chamber 10^a to which vapor is delivered by the conduit 27. A duct 12^a connects the chamber 10^a with a heating chamber 13^a.
 5 Tubes 15^a communicate with the chamber 13^a and extend upwardly through the chamber 4^a through the tubes 7^a to terminations below the tops thereof. A baffle 18^a is placed in the supply chamber 4^a between the
 10 outlet from the duct 3^a and the extensions of the tubes 7^a in the supply chamber to distribute the liquid around the tubes. A baffle 19^a surrounds the tops of the tubes 7^a, extending into the chamber 6^a, a deflector 20^a
 15 is adjustably supported above the tubes, and a baffle 25^a is supported above the baffle 20^a. A vapor conduit 27^a communicates with the top of the separating chamber 6^a above the baffles, and a liquid duct 29^a communicates
 20 with the bottom of the chamber below the baffles. A duct 30, controlled by the valve 30', connects the bottom of the chamber 10^a with the bottom of the chamber 10^a to permit the passage of water, steam or hot vapor
 25 from one chamber to the other. The duct 29^a discharges to a third effect comprising the expansion chamber 2^b connected by a duct 3^b with the supply chamber 4^b and by the duct 5^b with the separating chamber 6^b,
 30 the supply chamber and separating chamber being connected by the evaporating tubes 7^b which pass through the heating chamber 10^b to which vapor is admitted from the top of the chamber 6^a by the conduit 27^a. A
 35 duct 12^b connects the chamber 10^b with the heating chamber 13^b which communicates with the tubes 15^b extending through the chamber 4^b upwardly in the tubes 7^b to terminations below the tops thereof. A baffle
 40 18^b is disposed between the outlet from the duct 3^b and the ends of the tubes 7^b, which extend into the chamber 18^b. A baffle 19^b extends around the upper ends of the tubes 7^b, a baffle 20^b is held above these tubes, and
 45 a baffle 25^b is supported above the baffle 20^b. The conduit 27^b discharges vapor from the top of the chamber 6^b and the duct 29^b discharges concentrated liquid from the bottom thereof. A pipe 30^a, similar in function to
 50 the pipe 30, connects the bottoms of the chambers 10^a and 10^b.
 The heated fluid to be treated is admitted to the expansion chamber 2 under control, the pressure is relieved, the liquid is discharged
 55 from the bottom of the chamber through the duct 3 to the supply chamber 4 and separated vapor rises from the top of the expansion chamber through the duct 5 to the separating chamber 6, the liquid to be further
 60 treated being thus relieved initially of vapor. The supply chamber 4 is preferably kept full of liquid which fills the tubes 7 say to the level of the sheet 8. The temperature of the comparatively thin cylindrical shell of liquid in the lower ends of

the tubes 7 is raised by contact with the exterior surfaces of the lower ends of the tubes 15 heated by steam rising therein from the chamber 4. Vapor is thus generated in the supply chamber, primarily within the lower 70 ends of the tubes 7, and thereby liquid films are carried upward along the heating surfaces of the concentric tubes and evaporated. The vapor with the entrained liquid discharged from the tops of the tubes 7 strikes 75 the baffle 20 which spreads and deflects them downwardly and outwardly, the liquid passing over the lip of the baffle 19 to the bottom of the chamber 6 and the vapor rising around the baffle 25 to the conduit 27. The 80 fluid collected in the bottom of the chamber 6, being discharged through the duct 29 to the chamber 2^a and there permitted to expand, the contained vapor is separated, the liquid descending through the duct 3^a to 85 the supply chamber 4^a and the vapor rising through the duct 5^a to the separating chamber 6^a. The liquid in the supply chamber 4^a is carried in the form of films upwardly along the interior surfaces of the tubes 7^a 90 and the exterior surfaces of the tubes 15^a as previously described. In this second effect, however, the tubes 7^a and 15^a are less in number and larger in diameter than the tubes 7 and 15, so that with the higher 95 vacuum, the greater expansion of the vapor and the higher velocity of flow in the second effect, substantially the same amount of evaporation is obtained in the second as in the first effect. The vapor separated from the liquid in the chamber 6^a, being discharged through the conduit 27^a to heat the chamber 10^b and the separated liquid being discharged through the duct 29^a to the chamber 2^b, vapor contained in the liquid 100 rises through the duct 5^b to the chamber 6^b and the liquid remaining descends through the duct 3^b to the supply chamber 4^b, whence it is carried upwardly in films in contact with the heating surfaces of the tubes 7^b 110 and 15^b. These tubes are less in number and larger in diameter than the tubes 7^a and 15^a, being designed so that they will do substantially the same amount of evaporation as each of the preceding effects under 115 the different conditions; the third effect being subject to higher vacuum, whereby the expansion of the vapor and the velocity of flow are proportionately increased. The fluid delivered from the tubes 7^b to the chamber 6^b there has the vapor separated from the concentrated liquid, as previously described.

Fig. 2 represents the application of improvements of my invention to a single effect, 125 in which thin cylindrical columns of liquid mixed with vapor are carried upwardly between concentric tubes and the liquid discharged is returned for recirculation. The fluid to be treated is admitted under control 130

through the duct 31 to the expansion chamber 32, whence liquid descends through the duct 33 to the supply chamber 34, while the vapor rises through the duct 35 to the upper 5 part of the separating chamber 36. The tubes 37, which pass through the heating chamber 38, have their lower ends extended into the chamber 34 and their upper ends extended into the chamber 36. A heating 10 chamber 39 communicates with the lower ends of tubes 40 which extend upwardly through the chamber 34 into the tubes 37 to terminations below the tops of the latter, the tops of the tubes 40 having vents therein 15 as previously described. A conduit 41 extends downwardly from the bottom of the chamber 36, through the chamber 38, to an outlet near the bottom of the chamber 34, to return liquid from the separating to the 20 supply chamber.

Fig. 3 represents the application of improvements of my invention to a further form of single effect apparatus, in which liquid is carried upwardly between concentric tubes and returned to the supply chamber. The fluid to be treated is introduced through the duct 31^a into the chamber 32^a where vapor is separated from the liquid, the liquid descending through the duct 33^a 25 to the supply chamber 34^a and the vapor rising through the duct 35^a to the separating chamber 36^a. A heating chamber 39^a communicates with the lower ends of tubes 40^a which extend upwardly through the chamber 34^a 30 into the tubes 37^a to terminations below the tops of the latter, the tops of the tubes 40^a having vents therein as previously described. A return pipe or down comer 41^a connects the bottom of the separating chamber 36^a 35 with the supply chamber 34^a for the return of liquid discharged to the chamber 36^a, the vapor passing therefrom through the conduit 47^a. The outer tubes may have their lower ends, extending into the supply 40 chamber, beveled, as shown in Figs. 2 and 3 and as previously shown in my Mexican Patent No. 2014 of 1900.

Having described my invention, I claim:

1. In an evaporating apparatus, a heating chamber, a set of tubes extending through said heating chamber, a supply chamber communicating with said tubes, a separating chamber to which said tubes discharge, a second set of tubes disposed in said 50 tubes first named, a heating chamber communicating with the interior of said second set of tubes, and separating means having a duct for delivering liquid to said supply chamber and a duct for delivering vapor to 55 said separating chamber.

2. In an evaporating apparatus, a fluid duct, an expansion chamber into which said duct discharges, a liquid duct leading from the bottom of said chamber, a vapor duct 60 leading from the top of said chamber, a

supply chamber into which said liquid duct discharges, a separating chamber into which said vapor duct discharges, tubes connecting said supply chamber and said separating chamber, and a heating chamber through 70 which said tubes pass.

3. In an evaporating apparatus, a supply chamber, a separating chamber, one or more substantially vertical tubes connecting said chambers and extending into said supply 75 chamber, a heating chamber through which said tube or tubes extend, one or more tubes disposed in said tube or tubes first named and extending through said supply chamber, and a heating chamber communicating with 80 the ends of said second named tubes passing through said supply chamber.

4. In an evaporating apparatus, upright tubes, tubes within said tubes first named, said second named tubes having their tops 85 closed excepting air vents, a heating chamber surrounding said tubes, a heating chamber communicating with the lower ends of said second named tubes, a supply chamber communicating with the lower ends of said 90 first named tubes and a separating chamber with which the upper ends of said first named tubes communicate.

5. In an evaporating apparatus, a set of 95 upright tubes, a set of tubes disposed within said tubes first named, said second set of tubes having their upper ends within said first named tubes, a heating chamber surrounding said tubes, a supply chamber into which the lower ends of said first named 100 tubes extend, a heating chamber communicating with said second named tubes through the lower ends thereof, and a separating chamber in which the upper ends of said first named tubes extend.

6. In an evaporating apparatus, a supply chamber, a separating chamber, a heating chamber, evaporating tubes extending through said heating chamber, said tubes having their lower ends extended into said 110 supply chamber, a duct for delivering liquid to said supply chamber above the inlets to said tubes, tubes disposed within the first named tubes, and a heating chamber communicating with said second named tubes. 115

7. In an evaporating apparatus, a supply chamber, a separating chamber, a heating chamber, a set of tubes extending through said heating chamber, said tubes connecting said supply chamber and said separating 120 chamber, a second set of tubes extending through said first named tubes, a heating chamber communicating with said second named tubes, and a duct connecting said heating chambers. 125

8. In an evaporating apparatus, a set of substantially vertical tubes, a supply chamber into which the lower ends of said tubes extend, a duct for delivering liquid to said supply chamber, and a baffle extending 130

around the ends of said tubes in said supply chamber.

9. In an evaporating apparatus, a separating chamber, a set of tubes discharging into said chamber, a baffle in said chamber above said tubes, a second baffle in said chamber above said baffle first named, a duct for discharging liquid below said first named baffle and a conduit for discharging vapor 10 above said second named baffle.

10. In an evaporating apparatus, the combination of several effects each comprising an expansion chamber, a supply chamber, a duct connecting the bottom of said first 15 named chamber with said supply chamber, a separating chamber, and a duct connecting the top of said first named chamber with said separating chamber, the separating chamber of one effect being connected with 20 the expansion chamber of the succeeding effect.

11. In an evaporating apparatus, an effect comprising a heating chamber, a set of tubes passing through said heating chamber, a 25 supply chamber communicating with said tubes, and a separating chamber with which said tubes communicate, in combination with a second effect comprising a heating chamber, passing through said last named chamber a set of tubes of less number and larger 30 diameter than said first named tubes, a supply chamber communicating with said second named tubes, a separating chamber with which said second named tubes communi-

cate, and a duct connecting said first named 35 separating chamber with said second named supply chamber.

12. In an evaporating apparatus, an effect comprising a heating chamber, a set of tubes passing through said heating chamber, a 40 supply chamber communicating with said tubes, a separating chamber with which said tubes communicate, a second heating chamber, and tubes passing from said second heating chamber through said supply chamber into said tubes first named in combination with a second effect comprising a heating chamber, passing through said last named chamber a set of tubes of less number 45 and larger diameter than said first named tubes, a supply chamber communicating with said tubes of said second effect, a separating chamber with which said tubes of said second effect communicate, extending into said last named tubes a set of tubes 50 extending through said last named supply chamber, said tubes last named being of less number and larger diameter than said second named tubes, and a heating chamber 55 communicating with said tubes last named. 60

In witness whereof I have hereunto set my name this 16th day of July, 1910, in the presence of the subscribing witnesses.

JOSEPH E. DUNN.
